(57) **CLAIM**

The ornamental design for a housing for a paper shredder, as shown.

DESCRIPTION

FIG. 1 is a front elevational view of a housing for a paper shredder showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a top perspective view thereof shown on a slightly reduced scale.

The broken lines showing a crank handle and support members are for illustrative purposes only and form no part of the claimed design.
